UNITED STATES PATENT OFFICE.

MARK E. FERNALD, OF SAUGUS, MASSACHUSETTS.

SOLE-MARKING MACHINE.

1,393,105.

Specification of Letters Patent. Patented Oct. 11, 1921.

Application filed October 8, 1915. Serial No. 54,871.

To all whom it may concern:

Be it known that I, MARK E. FERNALD, a citizen of the United States, residing at Saugus, in the county of Essex and State of Massachusetts, have invented a new and useful Improvement in Sole-Marking Machines, of which the following is a specification.

The present invention relates to sole marking machines which are used in the manufacture of boots and shoes to mark the soles to be incorporated into shoes.

In the application for Letters Patent of the United States filed by me April 19, 1915, Serial No. 22,312, I have described a sole nail or tack retainer which is inserted into the bottom of a last for the purpose of holding the sole nails or tacks which secure the sole to the last bottom. The sole nail retainers are located at three separated points in the last bottom, namely, in the forepart, at the shank and in the heelseat. In order to register the sole on the bottom of the last the sole is first marked at the three places corresponding to the location of the three sole nail retainers on the bottom of the last. The nails are then driven through the sole at the marked points and the projecting points of the nails are then presented to the sole nail retainers and driven firmly therein.

The object of the present invention is to provide a sole marking machine which will mark the location of the sole nails on the sole.

To the accomplishment of this object and such others as may hereinafter appear the features of the invention relate to certain devices, combinations and arrangements of parts hereinafter described and then set forth broadly and in detail in the appended claims which possess advantages which will be apparent to those skilled in the art.

The various features of the present invention will be readily understood from an inspection of the accompanying drawings illustrating the best form of the invention at present known to the inventor, in which,

Figure 1 is a front elevation, partly in central longitudinal section, of the sole marking machine;

Fig. 2 is a plan;

Fig. 3 is a detail in side elevation, the shank marker being shown turned back and into inoperative position; and

Fig. 4 is a plan of a sole marked by the sole marking machine.

As shown in Fig. 4 the sole marking machine places a mark 1 in the forepart, a mark 2 in the shank, and a mark 3 in the heelseat, of a sole 4. The sole is marked while supported on a flat table 5 which is mounted at a convenient height upon legs 6.

The mark 1 is made by a prick-point 7 formed on the lower end of a rod 8 mounted to slide in a chamber 9. The point 7 is normally maintained retracted by a spring 10 which is coiled around the reduced shank of the rod 8 and interposed between the bottom of the chamber 9 and a striking head 11 on the upper end of the rod. The little circle surrounding the marks (Fig. 4) is made by the peripheral edge of the lower end of the rod 8 which is cut away to a comparatively sharp edge in the formation of the point 7. The chamber 9 is mounted on one end of an arm 12 which is pivoted on a V-shaped plate or gage 13 constructed to receive the toe end of the sole. The gage 13 is mounted to slide on the table 5. To this end the gage 13 is provided with slots 14 which embrace pins 15 (Fig. 1) loosely mounted on the table 5. The pins 15 are provided with enlarged heads 16 (Fig. 2) which frictionally engage the upper face of the gage 13 under the influence of springs 17 (Fig. 1) coiled around the pins 15 and interposed between the bottom of the table 5 and collars 18 on the lower end of the pins 15.

The mark 3 is made by a prick-point 19 constructed and supported in a similar manner to the prick-point 7. The point 19 is carried by an arm 20 which is pivoted on a V-shaped plate or gage 21 constructed to receive the heel end of the sole. The gage 21, like the gage 13, is mounted to slide on the table 5.

In order to slide the gages 13 and 21 in opposite directions to permit the introduction of a sole between them they are mounted on blocks 20^a and 20^b which slide in ways formed in the table 5. The blocks 20^a and

20^b are provided, respectively, with depending arms 22 and 23 which pass through slots 24 and 25 in the table 5. The arm 22 is connected by a link 22^a to one arm of a bell 5 crank lever 26 which is pivoted on a horizontal rod 27 carried by a frame 28 mounted intermediate the legs 6. The arm 23 is also connected by a link 23^a to one arm of a bell crank lever 29 also pivoted on the rod 27. The 10 lower arms of the bell crank levers 26 and 29 are connected to links 30 and 31 the lower ends of which are connected to a vertical rod 32 mounted to slide in lugs 33 formed on the frame 28. This connection between the 15 bell crank levers 26 and 29 forms a parallel motion device whereby the gages 13 and 21 are moved uniformly in opposite directions. To actuate the bell crank levers to separate the gages the bell crank lever 29 is provided 20 with a third arm 34 which is connected through a rod 35 to a treadle 36 pivoted at 36^a on one of the legs 6 (Fig. 2). The gages 13 and 21 are separated through the manipulation of the treadle 36 but are actuated in 25 the opposite direction to embrace the opposite ends of a sole positioned between them by a spring 37 one end of which is connected to the treadle 36 and the other end of which is connected to the frame 28.

30 In order to tip the prick-points 7 and 19 out of the way of the operative in positioning a sole between the gages 13 and 21 the arms 12 and 20 are provided, respectively, with depending pins 38 and 39 arranged to 35 engage blocks 40 and 41, secured to the table 5, during the separating movement of the gages, and thus tip the arms carrying the points about their pivotal connections with the gages (dotted lines Fig. 1).

40 The mark 2 is made by a third prick-point 41^a, similar in construction and mode of operation to the points 7 and 19, mounted on an arm 42 which is pivoted on a slide 43 mounted to slide transversely in a way 44 45 formed in the table 5. The location of the shank mark 2 is determined by a gage 45 constructed to embrace the opposite edge of the shank of the sole (Figs. 1 and 2). The gage 45 comprises a pair of arms 46 pivoted 50 on a block 47 which is mounted to slide longitudinally on an arm 48 projecting from a hub 49 pivoted on the arm 23 (Fig. 1). The arms 46 are provided with intermeshing 55 teeth 50 so that they move in unison during their pivotal movement on the block 47. The arms 46 are moved toward each other, until limited by cooperating stops 51, (Fig. 3), by a coiled spring 52. The connection between the gage 45 and the slide 43 comprises a bent arm 53 (Fig. 3) depending 60 from the slide 43 which carries a pin 54 upon which a projection 55 (Fig. 1) from the block 47 is pivoted.

To operate the machine the treadle 36 is

first depressed against the tension of the 65 spring 37 to separate the gages 13 and 21 and tip the points 7 and 19 into the dotted line position of Fig. 1. The sole is then positioned on the table 5 with the shank thereof 70 positioned between the arms 46 of the gage 45. The treadle is then released whereupon the spring 37 moves the gages 13 and 21 into engagement with the toe and heel ends of the sole. Owing to the V-shaped formation of the toe and heel gages the sole is shifted on 75 the table until the gages bear uniformly on the ends of the sole. During this shifting movement of the sole the gage 45, owing to the clamping engagement of its arms 46 with the edges of the sole, to the pivotal movement of the hub 49 on the arm 23 and the sliding connection between the block 47 and the arm 48, also shifts with the sole thereby 80 properly positioning the shank marker for the style of sole operated upon. As shown 85 in Fig. 2 the shank marker shifts transversely of the sole to accommodate the marker for right and left soles.

After the sole has been positioned in the manner described the striking heads 11 of 90 all the prick-points are struck with a hammer to project the points into the sole.

While the invention has been herein embodied in a sole marking machine for marking the location of the sole tacks on a sole it 95 will be apparent to those skilled in the art that various features of the machine may be advantageously employed in marking soles for other purposes.

It will be clear to those skilled in this 100 class of machines and with the general objects of the present invention in view that changes may be made in the details of structure the described and illustrated embodiment thereof being intended as an exploitation of its underlying essentials the features whereof are definitely stated in their true scope in the claims hereto appended.

What is claimed as new, is:—

1. A sole marking machine, having, in 110 combination, a support for the sole; and a forepart marker, a heelpart marker, and a shank marker for marking the location of the sole tacks on the sole; and means governed by the sole for shifting the shank 115 marker into different positions for right and left soles, substantially as described.

2. A sole marking machine, having, in combination, a support for the sole, a shank marker movable transversely of the sole, and means governed by the sole for moving the marker, substantially as described.

3. A sole marking machine, having, in combination, a forepart marker, a heelpart marker, a shank marker, gages constructed 125 to embrace the opposite ends of the sole for determining the location of the marks made by the forepart and heelpart markers on the

- sole, and a gage constructed to embrace the shank of the sole for determining the location of the mark made by the shank marker, substantially as described.
- 5 4. A sole marking machine, having in combination, a support for the sole, gages mounted to slide upon the support, a pivoted marker carried by each of the gages, and means for separating the gages and tipping the markers to permit the introduction of a sole between the gages, substantially as described.
- 10 5. A sole marking machine, having, in combination, a support for the sole, gages constructed to embrace the opposite ends of the sole on the support, and means for separating the gages to permit the introduction of the sole between them comprising a slide for each of the gages, a pair of pivotally mounted bell crank levers connected with said respective slides, a parallel motion device connecting the bell crank levers, and a treadle connection to one of the bell crank levers whereby the actuation of the treadle moves the gages uniformly in opposite directions, substantially as described.
- 15 6. A sole marking machine, having, in combination, a support for the sole, an arm pivoted beneath the support, a gage mounted to slide on the arm and constructed to embrace the opposite edges of the shank of the sole, and a shank marker mounted to move with the gage, substantially as described.
- 20 7. A sole marking machine, having, in combination, a support for the sole, an arm pivoted beneath the support, a gage mounted to slide on the arm and constructed to embrace the opposite edges of the shank of the sole, a slide mounted to slide on the support transversely of the sole and connected to move with the gage, and a shank marker mounted on said slide, substantially as described.
- 25 8. A sole marking machine, having, in combination, a marking device mounted to move longitudinally of the sole, a second marking device mounted to move transversely of the sole, means for relatively positioning said markers and a sole for the sole marking operation, and connections between the markers permitting the independent movement of the markers, substantially as described.
- 30 9. A sole marking machine, having, in combination, a fore part marker and a heel part marker movable longitudinally of the sole, a shank marker movable transversely of the sole, and means for relatively positioning said markers and a sole for the operation thereon of said markers.
- 35 10. A sole marking machine, having, in combination, a gage constructed to embrace a portion of a sole and a marker pivotally mounted on said gage for movement toward and from the face of the sole.
- 40 11. A sole marking machine, having, in combination, a gage constructed to embrace the end portion of a sole and a marker pivotally mounted on said gage for movement toward and from the face of the sole.
- 45 12. A sole marking machine, having, in combination, a shank marker, means for engaging opposite edges of the shank of a sole, and connections between the marker and the shank engaging means enabling said means to move said marker into different positions for marking right and left soles.
- 50 13. A machine for marking soles to designate the locations of the tacks for securing the soles to lasts, comprising a forepart marker, a heel marker, a shank marker, and gaging devices for relatively positioning said markers and a sole for the sole marking operation, said gaging devices being adjustable for different sizes and styles of soles.
- 55 14. A machine for marking soles to designate the locations of the tacks for securing the soles to lasts, comprising a forepart marker, a heel marker, a shank marker, and adjustable gages governed by the sole being marked and operative to relatively position the sole and said markers for the sole marking operation.
- 60 15. A machine for marking soles to designate the locations of the tacks for securing the soles to lasts, comprising a forepart marker, a heel marker, a shank marker, and gaging devices for positioning a sole for the operation of said markers, said markers being arranged to maintain a predetermined relationship to each other in all of their marking positions.
- 65 16. In a machine for marking soles to designate the locations of the tacks for securing the soles to lasts, a shank marker, and means for shifting said shank marker to cause it to mark either right or left soles at substantially the same relative point.
- 70 17. In a machine for marking a sole to designate the locations of the tacks for securing the sole to a last, a shank marker, devices adjustable to engage opposite edges of the shank portion of the sole and connected with said marker to control its marking position, and means for maintaining said devices in a plane substantially normal to the median line of the shank portion of the sole notwithstanding variations in the size and style of the sole.
- 75 18. In a machine for marking a sole to designate the locations of the tacks for securing the sole to a last, a shank marker, and means controlled by contact with the sole for positioning said marker in substantially the median line of the shank of either right or left soles.
- 80 19. A machine for marking soles to design-

nate the locations of the tacks for securing the soles to lasts, comprising a forepart marker, a heel marker, a shank marker, and means for positioning a sole for the operation of said markers, said shank marker being arranged to mark the sole at a point sub-

stantially at the intersection of the median lines of the fore and heel parts, and said forepart and heel markers being arranged respectively to mark the sole substantially 10 in said median lines.

MARK E. FERNALD.
